US00D740692S

(12) **United States Design Patent**
Christie et al.

(10) **Patent No.:** US D740,692 S
(45) **Date of Patent:** ** Oct. 13, 2015

(54) **CONTAINER**

(71) Applicant: **The Gillette Company**, Boston, MA (US)

(72) Inventors: **Vanessa Christie**, Boston, MA (US); **Andrew Anthony Szczepanowski**, North Attleboro, MA (US)

(73) Assignee: **The Gillette Company**, Boston, MA (US)

(**) Term: **14 Years**

(21) Appl. No.: **29/446,055**

(22) Filed: **Feb. 20, 2013**

(51) **LOC (10) Cl.** 09-03

(52) **U.S. Cl.**

USPC **D9/748**

(58) **Field of Classification Search**

USPC D9/737, 748, 749, 754, 755, 700, 686, D9/688, 689, 390; D3/201, 203.1, 203.2, D3/203.3, 203.4, 203.5, 203.6, 203.7, D3/203.8, 205, 273, 275, 294; D27/136; D28/44, 45, 73, 76, 77, 78, 82, 91; 206/228, 354; 29/401.1; 30/526, 541; D10/18, 30, 31, 37, 40, 45

(57) **CLAIM**

The ornamental design for a container, as shown and described.

DESCRIPTION

FIG. 1 is a perspective view of a container showing my new design;

FIG. 2 is a top view thereof;

FIG. 3 is a bottom view thereof;

FIG. 4 is a right view thereof;

FIG. 5 is a left view thereof;

FIG. 6 is a front view thereof;

FIG. 7 is a rear view thereof;

FIG. 8 is perspective view of the container shown in FIG. 1, in an opened orientation;

FIG. 9 is top view thereof;

FIG. 10 is a bottom view thereof;

FIG. 11 is a right view thereof;

FIG. 12 is a left view thereof;

FIG. 13 is a front view thereof; and,

FIG. 14 is a rear view thereof.

1 Claim, 9 Drawing Sheets
